ATTORNEYS.

UNITED STATES PATENT OFFICE.

JOHN F. GOLDING, OF CHICAGO, ILLINOIS.

ROCK-CRUSHER.

SPECIFICATION forming part of Letters Patent No. 238,676, dated March 8, 1881.

Application filed November 20, 1880. (No model.)

To all whom it may concern:

Be it known that I, JOHN F. GOLDING, of Chicago, in the county of Cook and State of Illinois, have invented a new and valuable improvement in Rock-Crushers; and I do hereby declare that the following is a full, clear, and exact description of the construction and operation of the same, reference being had to the annexed drawings, making a part of this specification, and to the letters and figures of reference marked thereon.

Figure 1 of the drawings is a perspective view. Figs. 2 and 3 are details.

This invention relates to crushers for rocks, &c.

The invention consists in the construction hereinafter described.

In the drawings hereto annexed, A represents a frame consisting of head-blocks B B and central bearing-blocks, C C, tied together and braced by rods D.

Journalized in bearings d d in bearing-blocks C C is a shaft, E, having middle portion, e, cam-shaped.

Just inside of bearings C C are risers F F, through whose lower holes, f f, passes shaft E, its body portion e resting in said holes, which are circular. Near the top of these risers are arranged on a line two elongated holes, f' f', elongated transverse the risers.

H H represent the crushing-jaws, whose rear ends, a a, rest on ledges b b, upon the inside of head-blocks B B. The faces of these jaws are corrugated, as shown at c.

I I represent studs, projecting from the sides of jaws H H at their front ends, said studs bearing in elongated holes f' f'.

K represents a wheel to which power is to be applied.

As wheel K and shaft E revolve, the cam e, turning in circular holes f f of risers F F, causes said risers to move up and down, and, by means of the elongated holes f' f' and the studs on jaws H H bearing therein, said jaws are caused to vibrate, and their corrugated faces coming together will crush anything thrown in between.

The employment of two segments with curved crushing-faces, either plain or corrugated, in connection with a mechanism for imparting to the same an oscillating motion, is not new. Segment-cams, a crank-shaft, and a yoke arranged together to produce a differential movement of the cams is also old in rock-breakers, and protection is only asked herein for the construction shown, described, and hereinafter claimed.

What I claim is—

The combination of jaws H H, having studs I I, risers F F, having elongated holes f' f' and circular hole f, and shaft E, having cam-shaped portion e, the whole arranged together and in a suitable frame, as and for the purposes described.

In testimony that I claim the above I have hereunto subscribed my name in the presence of two witnesses.

JOHN F. GOLDING.
